UNITED STATES PATENT OFFICE.

EDWIN WALKER, OF ERIE, PENNSYLVANIA.

CIGAR-TIP CUTTER.

SPECIFICATION forming part of Letters Patent No. 694,591, dated March 4, 1902.

Application filed May 17, 1901. Serial No. 60,681. (No model.)

To all whom it may concern:

Be it known that I, EDWIN WALKER, a citizen of the United States, residing at Erie, in the county of Erie and State of Pennsylvania,

5 have invented certain new and useful Improvements in Cigar-Tip Cutters; and I do hereby declare the following to be a full, clear, and exact description of the invention, such as will enable others skilled in the art to which 10 it appertains to make and use the same, reference being had to the accompanying drawings, and to the letters of reference marked thereon, forming part of this specification.

My invention relates to improvements in 15 cigar-tip cutters; and it consists particularly in improvements in the rotating cylinder, the cutter mechanism, and the tripping and stop mechanism, whereby the rotating cylinder is started and stopped.

20 The object of my invention is to produce a cigar-tip cutter in which the rotary cylinder is provided with a series of teeth or stops thereon adapted to engage and actuate the cutter-blade and tripping and stop mechanism adapted to engage teeth or stops on said cylinder and be disengaged therefrom, the tripping mechanism so operating to release the stop mechanism from engagement with the teeth or stops on the rotary cylinder as 25 30 not to interfere with the automatic reengagement of the stop mechanism with the teeth or stops on the rotary cylinder.

Another object of this invention is the construction of a cigar-tip cutter in a compact 35 form, so that it consists of comparatively few parts of simple construction, and also of improvements in the winding-key thereof.

I accomplish these objects by preferably 40 constructing the cigar-tip cutter with the rotary cylinder and the actuating-spring on the same shaft, which is mounted in a suitable frame, which shaft is provided with a winding-key, preferably consisting of a loop of wire inserted in holes in the shaft, thereby 45 50 providing a simple and inexpensive key and at the same time one which presents considerable gripping-surface to the hand operating it. In this construction the rotary cylinder is provided with peripheral teeth or stops and a stop-lever adapted to engage said teeth or stops and a tripping mechanism adapted to receive the tip of a cigar and also carrying a

cutter-blade pivoted thereto, together with trip-lever mechanism mounted thereon adapted to engage and be automatically disengaged from the stop-lever mechanism.

55 The mechanism above referred to which I have devised for these purposes is hereinafter fully set forth and described, and illustrated in the accompanying drawings, in which—

60 Figure 1 is a vertical section of the frame of a cigar-tip cutter on the line $x-x$ in Figs. 2 and 3, with the top thereof removed, showing a view in elevation of the mechanism of a cigar-tip cutter embodying my invention. 65 Fig. 2 is a plan view of the top of the cigar-tip cutter with the top of the case removed, portions of the lower part thereof broken away. Fig. 3 is a vertical section of the frame or case of the machine on the line $y-y$ in Fig. 1 and with the top thereof removed, showing another view, partially in elevation and partially in section, of the mechanism of the cigar-tip cutter. Fig. 4 is a sectional view of the upper part of the cigar-tip cutter 70 on the line $z-z$ in Fig. 2, showing the tip of a cigar in dotted lines inserted into the tip-opening preparatory to cutting the tip therefrom. Fig. 5 is a like sectional detail showing the mechanism operated and the tip of 75 the cigar cut off. Fig. 6 is a detail showing a plan view of the stop-lever and its bearing-pivot.

80 In these drawings thus illustrating my invention, A is the frame or case of the cigar-tip cutter, the top being provided with an opening A' for the insertion of the tip of a cigar, as illustrated in Figs. 4 and 5. In this frame or case there are supports $a-a'$, in which a transverse shaft B is journaled, upon which 85 shaft I mount an actuating-spring C and a rotating cylinder D. One end of the shaft B projects out of the side of the frame A, and through the end of which shaft I make holes, in which I place a winding-key B', made of 90 parallel rods b b', preferably in the shape of a staple, as illustrated in Fig. 3. This construction of winding-key is easily made and secured in the shaft B and when in place 95 presents a much larger gripping-surface for the fingers of the operator when winding up the spring C than is the case with the single pin ordinarily used as a winding-key in cigar-tip cutters.

The rotating cylinder D, I preferably make in the form of a disk having a flange on one side thereof. The periphery of this cylinder is provided with stops or teeth d , adapted to engage a shoulder e in a stop-lever E, which stop-lever E is pivoted to the frame A and is provided with a retracting-spring F, which engages a stud e' on the lever E and operates to bring the shoulder e on the stop-lever into engagement with the stop or teeth d , the upward movement thereof being preferably limited by a stop e^1 thereon contacting with the hub D' of the cylinder D. For further insuring this engagement the inner face of the flange on the rotating cylinder D is preferably provided with cam-surfaces d' , which engage a lateral stud e^2 on the stop-lever E and operate to automatically bring the shoulder e of the stop-lever E into contact with the teeth d regardless of the action of the spring F. In the top of the case A, I mount a tripper H, directly under the opening A' in the top of the case, which tripper is provided with lateral ribs h , which slide up and down in grooves a^2 a^2 in the frame A, as shown in Fig. 2. In the top of the tripper H, I make an opening H', adapted to receive the tip of a cigar, as illustrated in Figs. 4 and 5. From the top of the tripper H there are arms h' and h^2 , which extend downward on each side of the rotary cylinder D, as illustrated in Fig. 3. The arm h^2 is provided with a shoulder h^3 , adapted to contact with the cylinder-hub D', as shown in Fig. 5. On the arm h^2 there is a lateral extension I, which has a downward extension I' thereon, the lower end of which is pivoted to a link G, one end of which is pivoted to the frame A, and it is also provided with a retracting-spring to raise the tripper H up to and retain it in its normal position, as illustrated in Figs. 1, 3, and 4, yet permits the tripper H to be depressed, as illustrated in Fig. 5. Upon the extension I of the arm h^2 there is centrally pivoted an oscillating arm J, the lower end of which is adapted to contact with a lateral projection e^3 on the stop-lever E during the downward movement of the tripper mechanism. The arm J is also provided with a laterally-projecting weight-arm K, the downward movement of which is limited by a shoulder i on the downward extension I' of the lateral extension I, which weight operates to normally move the upper end of the arm J inward, so that the lower end of the arm J will engage the projection e^3 on the stop-lever E during the downward movement of the tripper H. The upper end of the arm J is provided with a lateral extension J', which overhangs the periphery of the cylinder D, as illustrated in Fig. 3, and when the tripper H is moved downward until the rotary cylinder D is released one of the teeth or stops d thereon engages the extension J' on the arm J and moves the upper end thereof outward and disengages the lower end of the arm J from the stop-lever E, so as to allow it to operate, and

as soon as the tripper H returns to its normally upraised position the weight K, operating on the arm J, returns it to its normal position, with its lower end in engagement with the stop-lever E, as illustrated in Figs. 1 and 3, with the mechanism again ready for cutting a cigar-tip. The cutter-blade in this mechanism can be made, mounted, and operated in several different ways; but I preferably make it in the form of a yoke L, the lower ends l l' of the arms thereof extending downward on the inside of the tripper-arms h' h^2 , where the arms l l' are pivoted thereto, so that the yoke L will swing freely thereon. On the top of the yoke L there is a cutter-blade M, secured so that the edge thereof will travel directly across the lower end of the opening H' in the tripper H, as illustrated in Figs. 1, 4, and 5. On the back of the arms l l' there are weights m m , provided with shoulders m' , which contact with the edges of the tripper-arms h' h^2 when the edge of the cutter-blade M has passed the opening H' in the tripper H and stops the forward movement of the yoke L, as clearly shown in Fig. 5. These weights m m also operate to throw the yoke L back to its normal position, as shown in Figs. 1, 2, and 4. To limit the backward movement of the yoke L, the arm l' thereof has a forwardly-projecting extension l^2 thereon provided with a lateral projection l^3 , which engages the edge of the tripper-arm h^2 when the yoke L is in its normal position. The part of the yoke L to which the blade M is secured is provided with a projection L' , which extends between the weights m m and is adapted to be engaged by the teeth or stops d on the rotary cylinder D when the tripper is depressed, so that when the cylinder D rotates it operates to drive the yoke L and the blade M, mounted thereon, forward across the opening H' in the tripper H, as illustrated in Fig. 5.

In operation when a cigar is inserted into the opening A' in the case A it contacts with the opening H' in the tripper H. If the cigar is then pressed downward, it moves the tripper H downward, which operates through the arm J to press the stop-lever E downward until the rotary cylinder D is released. Meanwhile the yoke carrying the cutter-blade M and the projection J' on the arm J have been brought into line with the teeth or stops d on the cylinder D, which cylinder when released moves forward and carries the yoke L and cutting-blade M thereon across the opening H' in the tripper H, so as to sever the tip of a cigar projecting downward through the same, and simultaneously one of the teeth or stops d on the rotary cylinder D has acted upon the upper end of the arm J to disengage the lower end thereof from the stop-lever E, which instantly engages the next tooth or stop d on the cylinder D and stops its rotation, and when the cigar is removed from the opening H' the tripper automatically returns to its normal position, with the lower end of

the arm J in engagement with the stop-lever E, the weights m m meanwhile returning the yoke L to its normal position and again ready to operate.

5 I have thus shown and described convenient mechanism for utilizing my invention so as to enable others to construct and operate same; but I do not desire to confine myself to the particular construction of my invention herein shown and described, as it is clearly obvious to those skilled in the art to which it appertains that the features thereof can be readily utilized in the manufacture of cigar-tip cutters in various forms of construction and arrangement of same, or all of the parts of the mechanism thereof, and good results attained without in any manner departing from the spirit of my invention. Therefore

20 What I claim as new, and desire to secure by Letters Patent of the United States, is—

1. In a cigar-tip cutter, a rotary cylinder, a stop mechanism, a tripping mechanism adapted to operate the stop mechanism, and a cutter mechanism carried by the tripping mechanism and adapted to be brought into engagement with the rotary cylinder by the action of the tripping mechanism, substantially as set forth.

2. In a cigar-tip cutter, a rotary cylinder, teeth or stops thereon, stop mechanism adapted to engage said teeth or stops, a tripping mechanism adapted to disengage said stop mechanism, a cutter mechanism mounted on the tripper and adapted to be moved into engagement with the teeth or stops on the cylinder thereby, substantially as set forth.

3. In a cigar-tip cutter, a rotary cylinder, a tripper having a cigar-tip opening therein, a cylinder stop mechanism operated by said tripper, and a cutter mechanism mounted on the tripper and adapted to be actuated by the rotary cylinder when the tripper is depressed, substantially as set forth.

4. In a cigar-tip cutter, a frame, a spring-actuated rotary cylinder mounted therein, teeth or stops and cam-surfaces on said cylinder, stop-lever mechanism adapted to engage the teeth or stops and the cams on said cylinder, a tripper having an opening therein

to receive a cigar-tip, mechanism on said tripper for engaging said stop-lever, and a cutter mechanism engaging said tripper and adapted to be moved thereby into engagement with the teeth or stops on the rotary cylinder, substantially as set forth. 55

5. In a cigar-tip cutter, a frame, a spring-actuated rotary cylinder mounted therein, teeth or stops on said cylinder, a stop-lever engaging the teeth or stops thereon, a tripper mounted in said frame so as to move up and down therein, and having a cigar-tip opening therein, a swinging arm mounted on said tripper so as to engage said stop-lever, a lug or extension on said arm adapted to be brought 60 into engagement with the teeth or stops on said rotary cylinder by the action of the tripper, and a cutter-blade mechanism mounted on the tripper and adapted to be brought into engagement with the teeth on the rotary cylinder by the operation of the tripper, substantially as set forth. 70

6. In a cigar-tip cutter, a frame, a spring-actuated rotary cylinder mounted therein, teeth or stops on said rotary cylinder, a stop-lever adapted to engage the teeth or stops thereon, a tripper mounted in said frame so as to move up and down therein, arms thereon projecting down on each side of the cylinder, a cutter mechanism pivoted on said arms, so as to move up and down with said tripper, a downward extension on one of the tripper-arms, a link pivoted to said extension and to the frame, spring mechanism for raising said tripper to its normal position, 85 and an arm on said tripper adapted to engage the stop-lever during the downward movement of the tripper, substantially as set forth.

7. In a cigar-tip cutter, the combination of a spring-shaft, and a winding-key therefor 90 consisting substantially of U-shaped rod inserted in holes in said shaft, substantially as set forth.

In testimony whereof I affix my signature in presence of two witnesses.

EDWIN WALKER.
